Atty.*

UNITED STATES PATENT OFFICE.

EDWARD WALTER WOLFE KEENE, OF BRISTOL, ENGLAND.

FILTERING APPARATUS.

Application filed April 20, 1922. Serial No. 555,701.

To all whom it may concern:

Be it known that I, EDWARD WALTER WOLFE KEENE, a subject of the King of Great Britain and Ireland, and residing at 5 15 to 19 Coronation Road, Bristol, in the county of Gloucester, England, have invented a certain new and useful Improved Filtering Apparatus (for which I have filed application in England March 11, 1921, application No. 5097/22), of which the following is a specification.

This invention relates to filtering apparatus of the kind comprising a rotary member or members adapted to be partially submerged in the material to be filtered, and in which a partial vacuum is created for the purpose of causing the solid or semi-solid material to be removed, to adhere to the outer surface of the filtering member or 15 members and whereby compressed air may subsequently be admitted to the interior of the rotary member or members to assist in the removal of such adherent solid or semi-solid material.

20 The object of the present invention is to increase the effectiveness of filtering apparatus of the above kind by providing an improved form of rotary valve, whereby the creation of a vacuum and the admission of compressed air, water and/or other medium to the interior of the filtering members may be adequately controlled, and the invention consists in filtering apparatus of the kind referred to having a rotary valve comprising 25 a rotary ported member cooperating with a fixed member surrounding said rotary member and having one or more suitable outlets provided therein, and one or more adjustable sliding members located between the rotary member and the fixed member whereby the functions of the ports may be controlled and/or regulated.

The invention also consists in apparatus as set out in the preceding paragraph, in 30 which the valve is provided with suitable adjustable packing between the fixed and rotary members.

The invention further consists in apparatus of the above character in which the 35 valve is provided with means for regulating the period of filtration.

The invention still further comprises other details and arrangements hereinafter described or indicated.

40 55 The accompanying drawings illustrate one

convenient mode of carrying my invention into effect:

Figure 1 is a longitudinal section of a valve constructed in accordance with the invention;

Figure 2 is a transverse sectional elevation of the valve on the line II—II of Figure 1.

Figure 3 is an end elevation of the complete valve.

In carrying my invention into effect in one convenient manner, I form my improved valve with a rotary member *a* carried on a main shaft *b* and adapted to rotate therewith, the shaft *b* primarily serving to carry the rotary filtering member or members. The rotary member *a* is provided with a plurality of axially arranged passages *c* communicating at one end with the radial ports *d*, the other end being adapted to engage the ends of the tubes *e* supported in the member *f* which is keyed or otherwise secured to the shaft *b*.

From this it will be seen that the rotary member *a*, tubes *e* and their support *f* and also the rotary filtering member or members are adapted to rotate with the shaft *b*.

The ends of the axial passages *c* remote from the tubes *e* may, if necessary, be closed by means of removable plugs.

The tubes *e* correspond in number and axial relationship to the separate and distinct sectors into which each of the rotary filtering members is divided, each tube being connected in series with the corresponding sector in all the rotary members.

Surrounding the rotary member *a* is a fixed housing *h*, which may be removably secured to the fixed port *i* of the plummer block *j* by means of studs *k*, an annular space *l* serving as a space for any suitable form of packing between the fixed housing *h* and the rotary member *a*, the valve housing thus forming a gland and stuffing box which may be tightened or adjusted in connection with the packing.

If necessary or desirable, the valve cover *m* may be so constructed as to co-operate with the rotary member *d* to form an additional gland and stuffing box at the front end of the valve housing.

The housing *h* is further provided with a cap or cover *m* secured thereto by means of studs *n*, which end cover offers the advantage that being readily removable it enables cleaning operations to be readily executed.

without the necessity of dismantling the valve.

The cover *m* may also be provided with a suitable external bearing with the object of supporting the weight of the housing *h* and thereby minimize wear on the valve face.

The valve housing *h* is provided with one or more outlets (two being shown), the upper one at *o* functioning as an outlet for wash solution and an outlet *p* for filtrate, an air inlet *q* being also provided for breaking the vacuum when required, and an air outlet *q* for relieving filtrate suction.

In order that the valve may fulfil its functions the ports *d* in the rotary member *a* are divided into sets for effecting the various controls, for example, the ports 2 are filtrate ports, the ports 3 low vacuum wash solution ports, the port 4 is for admission of pressure air for removing material from the outer surface of the rotary filter members, and the port 5 is for pressure air exhaust.

In order that the functions of these various ports may be regulated I provide a slide or other adjustable member *r* having ports *r'*, by which means the filtrate and wash solutions are separated and the quantity of either or both may be regulated, the second adjustable member *s* having ports *s'* serving to control the period of filtration, thus providing for differences in the character of the materials treated as, for example, those which cake rapidly and wash and dry slowly or vice versa.

As will be seen from the drawing these adjustable members are adapted to slide in an annular groove located between the rotary member *a* and the fixed housing *h* and are operated and fixed by links *t* cooperating with slots *u* in the valve cover *m*, the adjustments being made by means of the screwed links *t* passing through lugs *u* on the cover *m* and being secured thereto by means of nuts *v*.

It will be understood that the device is not to be limited to any particular form or construction of filtering apparatus nor to any number of rotary members nor to any particular size or shape of same, or the number of sectors or other shape into which each rotary member may be sub-divided, also the manner of connecting the valve to the rotary filtering members or their sectors and the means adapted for operating the adjustable slide members being varied as may be found expedient or desirable.

Furthermore, the provision of means for effecting the lubrication of the moving parts is to be made and various details of construction may be modified and various me-

chanical equivalents employed to the construction shown as may be found necessary to meet any particular practical requirements which may have to be fulfilled.

Having now described my invention what I claim as new and desire to secure by Letters Patent is:—

1. In filtering apparatus of the type referred to, the provision of a rotary valve comprising a rotary ported member, a fixed member co-operating with and surrounding said rotary member and having outlets provided therein and an adjustable sliding member located between the rotary member and the fixed member and having ports whereby the functions of the ports of the rotary member may be controlled and regulated, substantially as described and for the purpose set forth.

2. Filtering apparatus as claimed in the preceding claim, in which the valve is provided with a suitable adjustable packing between the rotary and fixed members, substantially as described and for the purpose set forth.

3. Filtering apparatus as claimed in claim 1, characterized by the provision of a second adjustable sliding member adapted to regulate the period of filtration.

4. In filtering apparatus of the character described, a rotary valve comprising a rotary ported member, a fixed member co-operating with and surrounding said rotary member and having outlets therein, an adjustable sliding member located between the rotary member and the fixed member having ports whereby the functions of certain of the ports of the rotary member may be controlled, and a second adjustable sliding member associated with other of the ports of the rotary member to regulate the period of filtration.

5. In filtering apparatus of the character described, a rotary valve comprising a rotary ported member, a fixed member co-operating with and surrounding said rotary member and having outlets therein, an adjustable sliding member located between the rotary member and the fixed member having ports whereby the functions of certain of the ports of the rotary member may be controlled, a second adjustable sliding member associated with other of the ports of the rotary member to regulate the period of filtration, and independent adjusting means for each adjustable sliding member.

In testimony whereof I have signed my name to this specification.

EDWARD WALTER WOLFE KEENE.
